UNITED STATES PATENT OFFICE.

JEFFERSON GORDIN, OF SEARSBOROUGH, IOWA.

DESIGN FOR A HARNESS-SLIDE D.

SPECIFICATION forming part of Design No. 29,730, dated November 29, 1898.

Application filed October 24, 1898. Serial No. 694,481. Term of patent 14 years.

To all whom it may concern:

Be it known that I, JEFFERSON GORDIN, a citizen of the United States, residing at Searsborough, in the county of Poweshiek and State of Iowa, have invented and produced a new and original Design for a Harness-Slide D; and I do hereby declare the following to be a full, clear, and exact description of the same, reference being had to the accompanying drawings, forming a part thereof.

This invention relates to new and useful designs for harness-slide D's; and it consists of the configuration of the unitary device hereinafter set forth.

15 In the accompanying drawings, Figure 1 is a perspective view of the D, looking toward the front thereof. Fig. 2 is a similar view looking toward the rear of the D. Fig. 3 is a central longitudinal vertical section of the device.

20 Referring to the drawings, wherein similar numerals are utilized to indicate corresponding parts in the several views, the numeral 1 designates the main body of the D, which is substantially V-shaped and has two flat sides

2 with curved edges 3. The said body of the 25 D also has a front bifurcation or opening 4, the walls of which are curved, and connecting the parts of the D at the location of this bifurcation are bars 5, 6, and 7, which follow as to their positions the general curvature of 30 the bifurcation, and the bar 6 is concavo-convex, as clearly shown by Fig. 3. The outer surfaces of the bars 5 and 7 are also concave, and connecting the front ends of the sides 2 are cross-bars 8, which slightly taper toward 35 their outer terminations. The opposite sides 2 converge toward the rear and merge into a rounded loop 9.

Having thus described the invention, what is claimed as new is—

40 The design for a harness-slide D, as herein shown and described.

In testimony whereof I affix my signature in presence of two witnesses.

JEFFERSON GORDIN.
